UNITED STATES PATENT OFFICE.

EDWARD B. TOLL, OF YAKIMA, WASHINGTON.

TRUSS.

1,320,105.

Specification of Letters Patent.

Patented Oct. 28, 1919.

Application filed April 7, 1919. Serial No. 288,121.

To all whom it may concern:

Be it known that I, EDWARD B. TOLL, a citizen of the United States, residing at Yakima, in the county of Yakima and State 5 of Washington, have invented a new and useful Truss, of which the following is a specification.

This invention relates to trusses or rupture appliances, the principal object being 10 to provide a rupture appliance which will not rub the person and which will be comfortable to the same, in general.

A further object of the invention is to provide a rupture appliance which embodies 15 a novel truss block and pad which will press upon the rupture and hold the same firmly and at the same time being comfortable to the wearer.

Another object of the invention is to provide 20 a rupture appliance which embodies an improved truss block and inflatable pad therefor, that will obviate rubbing or chafing and adding to the comfort of the wearer generally.

25 An additional object of the invention is to provide an appliance of the above described character which is simple in construction, which consists of few parts, and which may be manufactured and sold at 30 a minimum cost.

With the above and other objects and advantages in view, the invention consists 35 of the combinations of elements, constructions and formations, and general assemblage which will hereinafter be fully set forth and claimed.

On the drawings:—

Figure 1 is a front elevation of a truss constructed in accordance with my invention;

Fig. 2 is a longitudinal sectional view of the same taken on line 2—2 of Fig. 1.

Referring in detail to the drawings wherein like characters of reference denote like 45 parts, the numeral 5 denotes a truss block which has its opposite longitudinal sides tapered toward one end, the transverse ends of the block being rounded. This specific shape of block is not essential but it is particularly adapted to one type of wound, it being understood that different shapes of blocks are required for different types of wounds.

The inner face of the block 5 is recessed 50 or concaved as indicated at 6. A recess 7

is formed at the wide end of the block 5 and at its concaved face and defines an overhanging wall 8. An opening 9 is provided in the overhanging wall 8 which extends clear through the wide end of the block 5. 60

An inflatable rubber pad 10 is removably mounted in the concaved face of the block 5 and is provided with the usual inflating stem 11. This inflating stem 11 is disposed upon one side of the inflatable pad near 65 its wide end. The recess 7 accommodates the flange or collar of the inflating stem 11, the inflating stem 11 being extended through the opening 9 and a cap 12 inserted upon the end of the same. When 70 the pad 10 is inflated the inner side thereof is slightly accommodated in the concaved face of the block 5.

A securing belt 13 is attached to the outer face of the block 5 by a securing strap 14. 75 The belt 13 is adapted to be passed around the waist of the wearer and its ends secured together by a buckle 15 mounted on one end of this belt. A band 16 has one end attached to the belt 13 and depends downwardly therefrom and is secured to the block 5 by fastening 17, the opposite end of the band 16 being attached to the belt 13 at the rear of the same. Both the belt 13 and the band 16 are formed of elastic material. 80

The embodiment of the invention herein shown and described is considered the preferred construction, but it will be understood that the same is susceptible to various 90 modifications, and that my limits of modification are only governed by the appended claims.

What is claimed is:—

1. A surgical appliance comprising a 95 truss block having its inner face concaved, an overhanging wall disposed at one end of the concaved face, one end of the block being provided with an opening which extends through the overhanging wall, a 100 pneumatic pad seated in the concaved face of the block including an inflating stem, the inflating stem extending through the opening in the overhanging wall and contacting with the pneumatic overhanging pad. 105

2. In a surgical appliance, a truss block having its inner face concaved and further provided with a recess at one end thereof which defines an overhanging wall, the wall being provided with an opening that ex- 110

tends through one end of the block, an inflatable pad positioned in the concaved face of the block, an inflating stem carried thereby and extending through the opening, a portion of the pad being accommodated in the recess, and means for securing the block to the wearer.

3. In a surgical appliance, a truss block, the block being provided with a concaved inner face and further provided with a recess at one end thereof which defines an overhanging wall, the wall being provided with an opening which extends through the end of the block, an inflatable pad positioned in the concave face of the block, an inflating stem carried thereby and extending through the opening, the means for attaching the inflating stem to the pad being accommodated in the recess, and means for securing the block to the wearer.

dated in the recess, and means for securing the block to the wearer.

4. In a surgical appliance, an elongated block having its inner face concaved, one end of the block being provided with an opening which is disposed substantially centrally of the opposed faces of the block and extends substantially parallel to these faces, an inflatable pad seated in the concaved face including an inflating tube which extends through said opening, almost the entire length of the stem being accommodated in the opening.

In testimony that I claim the foregoing as my own, I have hereto affixed my signature.

EDWARD B. TOLL.
